(57) **CLAIM**

The ornamental design for an electronic book, as shown and described.

DESCRIPTION

FIG. 1 is a front perspective view of an electronic book showing the first embodiment of our new design;

FIG. 2 is a front view thereof;

FIG. 3 is a back view thereof;

FIG. 4 is a top side view thereof;

FIG. 5 is a bottom view thereof;

FIG. 6 is a right side view thereof;

FIG. 7 is a left side view thereof;

FIG. 8 is a back perspective view thereof;

FIG. 9 is a front perspective view of an electronic book showing the second embodiment of our new design;

FIG. 10 is a front view thereof;

FIG. 11 is a back view thereof;

FIG. 12 is a top side view thereof;

FIG. 13 is a bottom view thereof;

FIG. 14 is a right side view thereof;

FIG. 15 is a left side view thereof;

FIG. 16 is a back perspective view thereof;

FIG. 17 is a front perspective view of an electronic book showing the third embodiment of our new design;

FIG. 18 is a front view thereof;

FIG. 19 is a back view thereof;

FIG. 20 is a top side view thereof;

FIG. 21 is a bottom view thereof;

FIG. 22 is a right side view thereof;

FIG. 23 is a left side view thereof; and,

FIG. 24 is a back perspective view thereof.

The broken lines in drawings show portions of the electronic book that form no part of the claimed design. The oblique

(Continued)

line shading in the drawings shows a transparent, translucent and highly polished or reflective surface.

1 Claim, 18 Drawing Sheets
